TRANSPARENT COVER FOR A PHONOGRAPH RECORD CHANGER OR SIMILAR ARTICLE

Earl E. Hoyt, Northvale, N.J., assignor to BSR (USA)
Limited, Blauvelt, N.Y., a corporation of New York

Filed Dec. 2, 1968, Ser. No. 14,730

Term of patent 14 years

Int. Cl. D14—01

U.S. Cl. D56—4

FIG. 2.

FIG. 3.

FIG. 4.

FIG. 1 is a perspective view of a transparent cover for a phonograph record changer or similar article, embodying the new design.

FIG. 2 is a plan view of the record changer cover of FIG. 1.

FIG. 3 is a vertical section on line 3-3 of FIG. 2.

FIG. 4 is a vertical section on line 4-4 of FIG. 2.

The dominant features of my new design are shown in full lines in the figures. The dot-dash line showing of a representative phonograph record changer and base therefor in FIG. 1 are for illustrative purposes only. Portions of the drawing figures have been stippled to indicate contrast in appearance.

I claim:

The ornamental design for a transparent cover for a phonograph record changer or similar article, as shown and described.
